[57] CLAIM

The ornamental design for a water craft, as shown and described herein.

DESCRIPTION

FIG. 1 is a perspective view of a water craft showing my new design;

FIG. 2 is a top plan view thereof;

FIG. 3 is a side elevational view thereof, the opposite side view being a mirror image of that shown;

FIG. 4 is a bottom plan view thereof;

FIG. 5 is a left end view thereof;

FIG. 6 is a right end view thereof;

FIG. 7 is a perspective view of a second embodiment of the water craft;

FIG. 8 is a top plan view of FIG. 7;

FIG. 9 is a side elevational view of FIG. 7, the opposite side view being a mirror image of that shown;

FIG. 10 is a bottom plan view of FIG. 7;

FIG. 11 is a left end view of FIG. 7; and,

FIG. 12 is a right end view of FIG. 7.
